Primary Examiner—Shanda Hill

(57) **CLAIM**

The ornamental design for a beverage container, as shown and described.

DESCRIPTION

FIG. 1 is a front perspective view of a beverage container, showing my new design;

FIG. 2 is a front elevation view thereof;

FIG. 3 is a top plan view thereof; and,

FIG. 4 is a bottom plan view thereof.

Where included, broken lines shown in the drawing disclosures are for illustrative purposes only and form no part of the claimed design.
